No. 833,001.

PATENTED OCT. 9, 1906.

J. PRESS.
BORING DEVICE.
APPLICATION FILED SEPT. 16, 1905.

UNITED STATES PATENT OFFICE.

JACOB PRESS, OF NEW YORK, N. Y.

BORING DEVICE.

No. 833,001.

Specification of Letters Patent.

Patented Oct. 9, 1906.

Application filed September 16, 1905. Serial No. 278,738.

To all whom it may concern:

Be it known that I, JACOB PRESS, a subject of the Czar of Russia, and a resident of the city of New York, borough of Brooklyn, in 5 the county of Kings and State of New York, have invented a new and Improved Boring Device, of which the following is a full, clear, and exact description.

The invention relates to a device for use in 10 conjunction with an ordinary brace and bit to enable the operator to bore a hole at right angles with the surface of the object in which the hole is bored.

The invention resides in certain special 15 features of construction and novel combinations of parts, which will be fully set forth hereinafter and particularly pointed out in the claims.

Reference is to be had to the accompanying 20 drawings, which illustrate, as an example, the preferred form of my invention, and in which—

Figure 1 is a side elevation of the invention. Fig. 2 is a sectional plan view on the 25 line 2 2 of Fig. 1. Fig. 3 is a vertical section taken through one of the telescopic extensions of the device and through a part of the base and a part of the cross member; and Fig. 4 is a sectional elevation on the line 4 4 30 of Fig. 1, particularly showing the gage for indicating the depth of the hole.

The invention is adapted to be used in connection with a brace and bit of essentially ordinary construction, the same comprising a crank part *a* and a stock or chuck *b*. As shown in Fig. 1, the stock is provided with one or more projecting lugs *b'* at its lower end, and these lugs are adapted to act in conjunction with the gage, as will be hereinafter described. The said stock or chuck is arranged to hold a bit *c* in the usual manner.

d indicates the base of the device, which is of flat plate-like form and has a central 45 opening *d'*, through which the bit operates. Rigidly secured to the base *d* at each side of the opening *d'* is a tubular standard *e*, and in these standards rods *f* are movable. Said rods have enlargements *f'* at their lower ends, 50 and the tubular standards *e* have contracted collars *e'* at their upper ends, which are adapted to engage the enlargements to prevent separation of the parts *e* and *f*. Each tubular standard *e* carries a spring *h*, and 55 these springs serve normally to lift the rods *f*

in the position shown in Fig. 3. The rods *f* are rigidly connected at their upper ends by a cross member *i*, and this is formed with an opening *i'* in its middle, through which opening a part of the stock *b* of the bit passes. 60 Said part of the stock *b* has an annular groove *b'* therein, and this is adapted to receive a key or screw *i'*, which is carried in the cross-piece *i* and prevents vertical displacement of the stock *b* with respect to the 65 cross-piece *i*.

Secured to the base *d* is a gage-rod *k*, which is graduated, as shown in Fig. 1, and which has a head *l* adjustable thereon, the desired position of the head on the gage-rod 70 being maintained by a set-screw *m*. The head *l* carries the shank *n* of a fork *o*, and *p* indicates a set-screw operating in the head and adjustably holding said shank in place. The fork *o* is adapted to straddle the bit, as 75 indicated in Fig. 1, and be engaged by the lugs *b'* of the stock *b*.

In the use of the invention the parts will be adjusted as shown and downward pressure exerted on the brace at the same time that 80 the instrument is rotated. This will cause the bit to engage the object in which the hole is to be formed, and the springs *h* will yield to permit the rods *f* to move down into the tubular standards *e*, thus allowing the bit to work 85 its way into the wood. At the same time the base *d* bearing on the surface of the wood and the arrangement of the standards *e* perpendicularly to the base insures that the bit enters the wood at right angles to the plane 90 on which the base is resting. In this manner a hole at right angles to the surface of the wood may be bored without the operator paying special attention to this point. If it is desired to gage the depth at which the hole 95 is formed, the head *l* of the gage device should be adjusted on the standard *k* according to the scale of graduations produced thereon, and when the predetermined depth has been reached the lugs *b'* will strike the 100 fork *o* and further downward movement of the bit will be prevented. At the same time the operator will be warned that the limit has been reached and may then reverse the 105 operation of the bit, withdrawing it from the wood or other work.

Having thus described the preferred form of the invention, what I claim as new, and desire to secure by Letters Patent, is—

1. In a device of the class described, the 110

combination of a base, a tool-carrying means having guided movement toward and from the base at a fixed angle thereto, a gage-rod attached to the base, and a gage adjustable on the gage-rod and adapted to limit the movement of the tool toward the base.

2. In an instrument of the class described, the combination of a base, a tool-carrying means, having guided movement toward and from the base at a fixed angle thereto, springs normally holding said tool-carrying means away from the base, and a gage supported from the base, and adapted to limit the movement of the tool toward the base.

15 3. In a device of the class described, the combination of a base having a central opening therein, tubular standards attached to the base at opposite sides of the opening, rods movable in the tubular standards, expansive springs arranged in the standards and engaging the rods, a cross-piece rigidly connecting the rods and adapted to be engaged by a tool, a gage-rod rising from the base, and a gage adjustable on the gage-rod 25 and adapted to be engaged by the tool.

4. In a device of the class described, the combination of a base, telescopic standards mounted thereon, a cross-piece connecting the movable members of the standards, a 30 boring-tool having its stock mounted to turn in the cross-piece, a gage-rod secured to the base, and a head adjustable on the gage-rod

and carrying a fork adapted to be engaged by the lower end of the stock.

5. In a device of the class described, the combination of a base, having an opening therein, tubular standards attached to the base at opposite sides of the opening, rods movable in the tubular standards, springs arranged in the standards and normally pressing the rods upward, a cross-piece rigidly connecting the rods at their upper ends, a brace having its stock mounted to turn in the said cross-piece, the said stock being adapted to carry a bit and having projecting lugs at 45 its lower end, and an adjustable gage adapted to be engaged by said lugs to limit the movement of the bit.

6. In a device of the class described, the combination of a base, tool-carrying means 50 having guided movement toward and from the base, a gage-rod attached to the base, a head adjustable on the gage-rod, and a fork having a shank adjustably secured to the head and adapted to limit the movement of 55 the tool.

In testimony whereof I have signed my name to this specification in the presence of two subscribing witnesses.

JACOB PRESS.
